CLAIM

The ornamental design for cork-lined container, as shown and described.

DESCRIPTION

FIG. 1 is a top left isometric view of the cork-lined container of the present invention;

FIG. 2 is a top view thereof;

FIG. 3 is a front view thereof; and,

FIG. 4 is a right side view, the left side being a mirror image thereof.

The portions of the cork-lined container illustrated in broken lines form no part of the claimed subject matter.
